(57) CLAIM

The ornamental design for a bottle for cologne and perfume, as shown and described.

DESCRIPTION

FIG. 1 is a top, front, right side perspective view of a bottle for cologne and perfume showing my new design;

FIG. 2 is a top plan view thereof;

FIG. 3 is a bottom plan view thereof;

FIG. 4 is a front elevation view thereof; and,

FIG. 5 is a left side elevation view thereof, the right side elevation view being a mirror image.

The broken lines in the drawings showing the bottle closure illustrate the portions of the design that form no part of the claim.
